(57) **CLAIM**

The ornamental design for a drawer for a three-dimensional printer, as shown and described.

DESCRIPTION

FIG. 1 is a top perspective view of a design for a drawer for a three-dimensional printer;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a top perspective view of the design of the drawer for a three-dimensional printer in an open position;

FIG. 9 is a front view of the design of the drawer for a three-dimensional printer in the open position;

FIG. 10 is a left side view of the design of the drawer for a three-dimensional printer in the open position;

FIG. 11 is a right side view of the design of the drawer for a three-dimensional printer in the open position;

FIG. 12 is a top view of the design of the drawer for a three-dimensional printer in the open position;

FIG. 13 is a bottom view of the design of the drawer for a three-dimensional printer in the open position;

FIG. 14 is a top perspective view of the design of the drawer for a three-dimensional printer in an open position;

FIG. 15 is a top perspective view of the design of the drawer for a three-dimensional printer in an open position; and,

FIG. 16 is a top perspective view of the design of the drawer for a three-dimensional printer in a partially-open position. The broken lines immediately adjacent to the shaded areas and define unshaded regions depict the bounds of the claimed design, while all other broken lines are directed to environment. The broken lines form no part of the claimed design.
